United States Patent Office

Des. 211,656
Patented July 9, 1968

211,656

SPATULA

Falle Uldall, Nykobing, Denmark, assignor to Hutzler Manufacturing Company, Long Island, N.Y., a partnership

Filed Jan. 31, 1967, Ser. No. 5,670

Term of patent 14 years

(Cl. D44—29)

FIG. 1 is a top plan view of a spatula showing my new design; and

FIG. 2 is a side elevational view of the spatula.

I claim:

The ornamental design for a spatula, substantially as shown.
